TYPEWRITING MACHINE

Russell G. Thompson, West Hartford, Conn., assignor to Underwood Elliott Fisher Company, New York, N. Y., a corporation of Delaware

Application September 4, 1936, Serial No. 99,378

3 Claims. (Cl. 248—24)

This invention relates to typewriting machines, and especially to devices for supporting and securing such machines in a manner to reduce the noise resulting from their operation.

5 Much of the noise incident to the use of typewriting machines results from the magnification of the sounds of the operating mechanism by reason of the transmission of such sounds, in themselves small, through the machine-frame to the 10 desk or working surface on which the machine rests, said surface acting as a sounding board, with a resulting magnifying effect.

Rubber or other resilient mountings, comprising 15 cushions of various kinds and intended to insulate against such transmission, are well known. The common characteristic of these prior devices, however, is that the resilient material is under compression, resulting in an obviously inefficient structure, because the immediate 20 increase in density increases the sound and vibration transmission qualities of the material. In addition, the constant pounding to which a typewriter is subjected during use has the cumulative effect of so distorting and compacting the resilient material as to render it absolutely valueless 25 as an insulator in a comparatively short time.

These disadvantages are overcome in this invention, in which the resilient material is placed 30 under tension, thus lessening its density and increasing the insulating value, and continued use, up to a reasonable limit, acts actually to improve the insulating qualities.

In view of the foregoing, a general object of 35 the invention is to provide an improved mount or foot for typewriters and like machines, of simple and inexpensive construction and effective to substantially prevent the transmission of operating noises from the machine to the desk platform or other structure upon which the machine 40 rests.

Other objects and advantages will hereinafter appear.

In the drawing,

Figure 1 is a fragmentary side elevational view 45 of a typewriter mounted on a desk platform, the mount or foot being shown in central section, and

Figure 2 is a perspective view of the typewriter foot.

A typewriter 3 has its frame 4 formed to receive 50 a set of four feet 5, the frame 4 having a series of holes, each threaded to receive a screw 6 for attachment of the typewriter feet thereto. In use the typewriter is usually positioned on the desk platform or table 7 which may be a part 55 of the usual secretarial desk wherein the type-

writer carrying platform is swingably mounted to the desk in the well known manner so that by tilting the platform, the typewriter is concealed within the desk when not in use.

The screw 6 may have a cylindrical head 8 having a slot therein to receive a screw driver bit for attaching the foot 5 to the typewriter. The screw head 8 fits snugly but removably in a cylindrical collar 9 having at its upper end an inturned rim 10 overlying the shoulder of the screw and adapted to be clamped between the screw head 8 and the typewriter frame 4. The cylindrical collar 9 constitutes the body portion of an inner member of the typewriter foot and has at its lower end an outwardly projecting bottom flange 11 disposed substantially normal to the axis of the screw 6. The typewriter foot also includes an outer member having a cylindrical wall 12 at the top of which is an inwardly projecting flange 13 overlying the flange 11 of the inner member, the flange 13 having a central aperture through which the body portion 9 projects so that the typewriter is spaced from the top flange of the outer member. The cylindrical wall 12 of the outer member extends substantially below the bottom 20 flange 11 and is adapted to rest directly upon the platform 7, the wall 12 having an outwardly directed flange 14 providing a broad area for contact with the platform.

It is to be noted that the respective flanges 11, 30 13 match and are in parallelism with each other, as are also the cylindrical wall 12 and the body portion 9. A resilient rubber ring 16 is interposed between the inner and outer foot members, being secured as by vulcanizing to the confronting faces 35 of the said members. That is, the rubber ring 16 is vulcanized to both the flanges 11 and 13, and to the outer surface of the collar 9 and the inner surface of the cylindrical wall 12 of the outer member.

At the outer margin of the bottom of rubber ring 16 is an integral bead or annular portion 21 disposed between the periphery of the bottom flange 11 and the wall 12 to keep these members from actual metal-to-metal contact. A similar 45 bead 22 is provided at the top of the ring 16, being disposed within the inner edge of the top flange 11 and the body portion 9.

Under load of the typewriter, the inner member is pressed downwardly and tends to further 50 separate the flanges 11 and 13 thus causing a stretching or tensioning of the rubber ring 16. The arrangement of the flanges 11, 13 with their confronting faces substantially matching each other, and being secured to the rubber ring 16 55

entirely over these matching faces, assures that the entire ring 16 be subjected to the tensioning stress imparted by the load of the typewriter. The ring 16, being under tension, has a greater vibration absorbing effect than were same put under a shearing or compression stress. The inner member of the typewriter foot is thus suspended, by the rubber ring 16, on the outer member and may move downwardly under the load of the typewriter or to absorb any vibrations occurring therein, to prevent transmission of these vibrations to the platform 7. The rubber beads 21, 22, although permitting any necessary downward movement of the inner member, prevent same from moving excessively in a lateral direction, thereby providing a relatively firm but yielding support for the typewriter.

The outer flange 14 of each typewriter foot may, in coaction with other devices secured to the platform 7, serve to maintain the position of the typewriter on the platform. As shown herein, a metal plate 17 may be of ample size as to underlie substantially the entire area of the typewriter and is secured to the platform 7 by screws 18. A felt mat 19 is interposed between the plate 17 and the platform 7 and is effective in damping sound vibrations emanating from the typewriter. The plate 17 has peripheral portions 20 overlapping a part of the flange 14 of the typewriter foot and coacts therewith to hold the typewriter in place on the platform during operation or, when the typewriter is tilted into the desk.

Variations may be resorted to within the scope of the invention, and portions of the improvements may be used without others.

Having thus described my invention, I claim:

1. A resilient foot for support of a typewriter on a platform, comprising in combination, an inner member having a cylindrical body portion adapted for attachment to the typewriter and a flange projecting outwardly from the bottom thereof substantially at right angle to the axis of said body portion, an outer member having a cylindrical wall embracing said inner member and having an inwardly projecting top flange overlying and matching the flange of said inner member in parallelism therewith, and a resilient ring interposed between said inner member and said outer member and vulcanized to the confronting faces of said inner and outer members, the body portion of said inner member reaching above said top flange and the cylindrical wall of said outer member reaching below the flange

of said inner member and being restable on a platform, to permit said resilient ring to tension freely under load of the typewriter.

2. A resilient foot for support of a typewriter on a platform, comprising in combination, an inner member having a hollow cylindrical body portion adapted to removably receive a shouldered screw therein for attachment of the foot to a typewriter, said body portion having an in-turned rim for clamping between the screw shoulder and the typewriter, said inner member having a flange projecting outwardly from the bottom thereof, an outer member having a cylindrical wall embracing said inner member and having an inwardly projecting top flange overlying and matching the bottom flange of said inner member in parallelism therewith, and a resilient rubber ring interposed between said inner and outer members vulcanized to substantially the entire confronting faces of said inner and outer members, the body portion of said inner member reaching above said top flange and the cylindrical wall of said outer member reaching below the flange of said inner member and being restable on a platform, to permit said resilient ring to tension freely under load of the typewriter.

3. A resilient foot for support of a typewriter on a platform, comprising in combination, an inner member having a cylindrical body portion adapted for attachment to a typewriter and a flange projecting outwardly from the bottom thereof substantially at right angle to the axis of said body portion, an outer member having a cylindrical wall embracing said inner member and having an inwardly projecting top flange overlying and matching the bottom flange of said inner member in parallelism therewith, and a resilient rubber ring vulcanized to the confronting faces of said inner and outer members, said resilient ring having an upper annular portion between the body of said inner member and the edge of the top flange and having a bottom annular portion between the edge of the flange of said inner member and the wall of said outer member, the body portion of said inner member reaching above said top flange and the cylindrical wall of said outer member reaching below the flange of said inner member and being restable on a platform, to permit said resilient ring to tension freely under load of the typewriter.

RUSSELL G. THOMPSON.
